UNITED STATES PATENT OFFICE

106,164

DESIGN FOR A COMBINATION HAT AND SHOE CASE

Colin D. Wilt, Chicago, Ill.

Application June 23, 1937, Serial No. 70,007

Term of patent 14 years

To all whom it may concern:

Be it known that I, Colin D. Wilt, a citizen of the United States, residing at Chicago, in the county of Cook and State of Illinois, have invented a new, original, and ornamental Design for a Combination Hat and Shoe Case, of which the following is a specification, reference being had to the accompanying drawing, forming part thereof.

In the drawing:

Fig. 1 is a perspective view of a combination hat and shoe case, in closed position.

Fig. 2 is a perspective view thereof in open position, showing my new design.

The characteristic feature of my design resides in the interior portions of the case.

I claim:

The ornamental design for a combination hat and shoe case as shown and described.

COLIN D. WILT.
